US0D1038801S

(12) **United States Design Patent** (10) Patent No.: **US D1,038,801 S**
(45) Date of Patent: ** Aug. 13, 2024

(54) **READER DEVICE FOR AN ANALYTE
DETECTION SYSTEM**

(71) Applicant: **Cue Health Inc.**, San Diego, CA (US)

(72) Inventors: **Ayub Khattak**, San Diego, CA (US);
Clinton Sever, San Diego, CA (US)

(73) Assignee: **CUE HEALTH INC.**, San Diego, CA
(US)

(**) Term: **15 Years**

(21) Appl. No.: **29/881,362**

(22) Filed: **Dec. 30, 2022**

Related U.S. Application Data

(60) Continuation of application No. 29/837,126, filed on May 2, 2022, now Pat. No. Des. 994,516, which is a continuation of application No. 29/741,308, filed on Jul. 10, 2020, now Pat. No. Des. 951,789, which is a division of application No. 29/710,660, filed on Oct. 24, 2019, now Pat. No. Des. 891,959, which is a division of application No. 29/647,395, filed on May 11, 2018, now Pat. No. Des. 869,311, which is a division of application No. 29/584,715, filed on Nov. 16, 2016, now Pat. No. Des. 820,130, which is a division of application No. 29/545,014, filed on Nov. 9, 2015, now Pat. No. Des. 774,407, which is a division of application No. 29/490,660, filed on May 12, 2014, now Pat. No. Des. 745,423.

CLAIM

We claim the ornamental design for a reader device for an analyte detection system, as shown and described.

DESCRIPTION

FIG. 1 is a top, front, and left side perspective view of a reader device, which forms a portion of an analyte detection system;

FIG. 2 is an exploded view thereof;
FIG. 3 is a left side view thereof;
FIG. 4 is a right side view thereof;

FIG. 5 is a top view thereof;

FIG. 6 is a bottom view thereof;

FIG. 7 is a front view thereof; and,

FIG. 8 is a rear view thereof.

The ornamental design which is claimed is shown in solid lines in the drawings. The broken lines formed by dashes show unclaimed subject matter and form no part of the claimed design.
